G. A. FILER

EGG CASE FLAT

Filed Oct. 6, 1926

UNITED STATES PATENT OFFICE.

GEORGE A. FILER, OF CORNELL, WISCONSIN.

EGG-CASE FLAT.

Application filed October 6, 1926. Serial No. 139,771.

This invention relates to egg case flats for egg shipping crates.

Egg case flats have heretofore been made of corrugated straw board and the like, provided with transverse grooves or cut-away portions for positioning the cellular filler. In general, however, flats of this type have been of such light weight, flimsy material that a backing or reinforcement was necessary to enable the flat to sustain the weight of the eggs resting on it.

It is therefore an object of this invention to provide an egg case flat formed of a single unreinforced sheet of fiber board, both surfaces of which are corrugated, which will possess greater strength and resiliency than previously known flats.

It is a further object of this invention to provide a simple, inexpensive egg case flat of efficient cushioning effect.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of an egg case flat embodying the principles of this invention.

Figure 2 is an enlarged sectional view taken substantially on line II-II of Figure 1.

Figure 3 is an end edge view of Figure 1.

Figure 4 is a fragmentary view of a modified form of my invention.

Figure 5 is a sectional view taken substantially on line V-V of Figure 4.

As shown on the drawings:

Reference numeral 1 indicates an egg case flat which in accordance with the principles of my invention is formed of a single sheet of relatively heavy sheet material, such as fiber board. The fiber board is preferably of about .030 of an inch thickness, since it has been found that board of that thickness when corrugated and used as an egg case flat does not require any backing or other reinforcement to sustain the eggs without buckling. The egg case flat 1 is provided with corrugations 2 formed by stamping or other suitable means and extending over the entire surface

of the sheet. As viewed from the top of the sheet, the corrugations 2 comprise ridges or nodes 3 and intermediate troughs or depressions 4. In accordance with the principles of this invention, transverse grooves 5 are formed at suitably spaced intervals by crushing the ridges 3 of the corrugations down to the plane of the troughs 4. These transverse grooves 5 it will be understood serve to receive the bottom edges of the cellular fillers commonly used in egg cases, the normal partitions of the filler extending into certain of the troughs 4. In this way the filler is securely positioned against displacement or collapsing.

It has been found that if a fiber board of substantially the thickness specified is corrugated as by stamping between male and female dies, that the corrugations are rendered extremely resilient. In fact it is practically impossible to permanently deform the corrugations by any sudden blow or by any ordinary weight to which the flats may be subjected. Furthermore the crushing of the corrugations to form the filler positioning grooves adds greatly to the rigidity and supporting strength of the flat. It is accordingly unnecessary to supply backing or other reinforcing means for the flat and because of this the cost of manufacture is relatively less than in the case of backed corrugated flats.

In Figures 4 and 5 there is shown a modified form of the flat illustrated in Figures 1 to 3 inclusive. In order to more definitely position the egg, a portion of the corrugations 2 between the grooves 5 is crushed as shown at 6. While the crushed portion 6 has been shown as substantially square or rectangular, it is obvious that it may equally as well be circular in outline. The depressed portion 6 should of course be positioned centrally of the cell formed by the partitions of the filler.

It will be apparent that a simple and inexpensive egg case flat has been devised that because of its natural strength and resiliency imparted by the corrugations, will efficiently support and cushion the eggs against crushing.

I am aware that many changes may be made, and numerous details of construction may be varied through a wide range without departing from the principles of this in-

vention, and I therefore do not purpose limiting the patent granted hereon, otherwise than necessitated by the prior art.

I claim as my invention:

- 5 As an article of manufacture, an egg case flat comprising a single corrugated sheet of fibrous material having filler positioning

grooves extending transversely of said corrugations, portions of said corrugations between said grooves being crushed to define 10 egg receiving spaces.

In testimony whereof I have hereunto subscribed my name.

GEORGE A. FILER.
